UNITED STATES PATENT OFFICE.

JOHN D. DU MONT, OF ALAMEDA, CALIFORNIA.

PATTERN.

Application filed October 25, 1926. Serial No. 143,898.

The present invention relates to improvements in pattern used for molding sand to provide a form for casting metal or the like. My invention has particular reference to a 5 pattern of the base member of a chimney which may be briefly described as a cast iron plate formed with a ring on one side over which the chimney fits and formed with a central hole thru which soot, ashes, etc. may 10 be removed from the chimney, a gate being provided on the opposite face of the chimney base for closing the opening. This gate is made slidable and requires for its support two guides which are undercut in the con- 15 fronting faces to provide grooves in which the gate is slidably received and supported. The present invention is particularly concerned with the undercut guides which cannot be permanently fixed to the pattern on ac- 20 count of their undercut which would break up the molding sand when the pattern is removed therefrom. For this reason, it has been customary to provide small removable guides which would stick to the molding sand 25 when the pattern is removed and were formed so as to allow of careful removal from the molding sand thereafter. This, however, is a tedious process and consumes considerable time.

30 The object of the present invention is to provide a more convenient means for providing the guide cavities in the molding sand and I utilize for this purpose disappearing guides made in such a manner that they can be ma- 35 nipulated from the side of the pattern and made to disappear into the pattern by a re- volving motion while the molding sand is still in place on the pattern and without dis- 40 turbing the molding sand. Further objects and advantages of my invention will appear as the specification proceeds.

The preferred form of my invention is illus- 45 trated in the accompanying drawing in which

Figure 1 shows a side view of my pattern as confined between the two sections of a mold commonly known as the drag and the cope;

Figure 2 is a plan view of the pattern;

Figure 3 a bottom plan view of the pattern;

50 And Figure 4 an enlarged sectional detail view taken along lines 4-4 of Figure 3.

While I have shown only the preferred form of the invention, I wish to have it understood that various changes or modifica- 55 tions may be made within the scope of the

claims hereto attached without departing from the spirit of the invention.

My pattern comprises the wood plate 1 having the upper face section of the pattern 2 secured to one side and the bottom face section 60 to the other side. The former is of conventional form and offers no novel features. The bottom face section comprises the two projecting guides 3 arranged in confronting re- 65 lation as shown in Figure 3. Each guide re- sembles in cross section a fragmentary cylinder and is pivoted within the plate 1 by means of an axial rod 4 in such a manner that the guide may be swung into the plate so as to completely disappear therein or may be pro- 70 jected upwardly into a position where its front face 6 inclines inwardly in the direction of the other guide and is adapted for cooperation with the latter in supporting a gate slid between the guides from the diverging 75 ends thereof. The two guides are operated by means of handles 7 arranged parallel to one of the side edges of the plate so that the guides may be operated at any time and without disturbing molding sand lying 80 against the face of the pattern. The manner of using my invention is very simple. The two mold sections 8 and 9 are clamped upon the pattern in any suitable manner as, for in- 85 stance, by bolts extending thru ears 11 pro- jecting from the end of the pattern. Molding sand is then introduced into one of the mold sections and tamped to make perfect contact with the pattern. The section first filled is then covered by means of a board and the en- 90 tire device turned upside down whereupon the second section is filled with molding sand and tamped. If the mold sections were now removed from the pattern without attention given to the guides 3, the undercut in the lat- 95 ter would break up the molding face of the sand and destroy the same. To avoid this, it is only necessary to manipulate the handles 7 whereby the two guides 6 are made to dis- 100 appear into the plate and allow the molds to be removed without any difficulty. To pro- vide sharper lines and a good support for the guides 3, a metal plate 12 may be embedded in the wooden plate 1 so as to be flush with the surface thereof and bearing elements 13 may 105 be fastened to the under face of the metal plate for supporting the axial rod of the guides 3.

I claim:

1. A pattern of the character described 110

- comprising a wooden board having a metal plate embedded in one face thereof so as to be substantially flush therewith, bearing elements secured to the bottom of the plate, and 5 a molding element pivoted in the bearing and formed for projection beyond the face of the metal plate and for withdrawal thereinto.
2. In a pattern for a chimney base casting, a pattern board having oppositely disposed recesses therein, an undercut projection disposed in each recess, said projection extending beyond the face of the board adjacent to the mold material, and being designed in the shape of a fractional cylinder so as to move 15 on the arc of a circle, and means rotatably supported in said board and extending outside of the board for rotating said projection.
3. In a pattern for a chimney base casting having undercut guides at the opposite edges 20 thereof, a pattern board having recesses therein adjacent to the positions of said undercut guides, a projection rotatably disposed in each recess and being formed in the shape of a fractional cylinder; an axial rod 25 secured to each projection for swinging the same; bearings inside of said board for rotat-
- ably supporting said rods in the board, said rods extending outside of said board so as to be manually rotated for withdrawing said projections from the undercut position.
4. In a pattern for a casting having undercut members at the opposite edges thereof, a pattern board having recesses therein adjacent to the positions of said undercut members, a plate embedded in the recessed face of the board, said plate having elongated apertures above said recesses; bearings depending from said plate into said board; projections in said recesses projecting thru said apertures of said plate, said projections being so designed as to form the shape of the undercut above the plate and to be movable in said recesses on the arc of a circle; and 35 axial rods on said projections being rotatably supported in said bearings, and extending outside of said board so as to permit the withdrawal of said projections from the undercut position.

In testimony whereof I do hereby affix my signature.

JOHN D. DU MONT.
